MERCURY SWITCH

Ernst-Walter Rickmeyer, Berkeley, Ill., assignor
to Jefferson Electric Company, Bellwood, Ill., a
corporation of Illinois

Application October 11, 1945, Serial No. 621,813

9 Claims. (Cl. 200—80)

1

The present invention relates to mercury switches of the type where a switch envelope, at least in effect, is provided with two chambers adapted alternatively to receive and hold a body of mercury. One of the chambers is provided with two electrical contact members insulated from each other and electrically communicating with the interior of the chamber. The body of mercury while in this chamber bridges these two members so as to complete the electrical circuit through the switch. Upon proper manipulation of the switch, the mercury is caused to move into the second chamber so as to break the connection between the electrical contact members, thereby opening the circuit through the switch.

In some types of mercury switches that have been developed, the two chambers are separated by a wall or partition that is provided with restricted passages, or other such means, through which the mercury flows in passing from one chamber into the other. The mercury is caused to flow from one chamber into the other by centrifugal force resulting from rotating or spinning the mercury switch.

The switch forming the subject matter of the present invention entirely eliminates the use of the partition and the orifice, and provides a mercury switch that is ideally suited for centrifugal switches operated by slowly rotating or spinning the switch envelope to create the centrifugal force. Because of the low rate of spin, however, the centrifugal force that is available is such as to create considerable problems where the perforated partition is used to separate the two chambers.

It is an object of the present invention to provide a mercury switch that is ideally suited for low spin operation and that is relatively inexpensive and simple to manufacture and assemble.

The present switch is well suited for applications where accurate timing in a delayed action circuit is required. The time delay characteristics of this switch can be pre-determined within very close limits.

The foregoing constitute some of the principal objects and advantages of the present invention, others of which will become apparent from the following description and the drawings, in which

Fig. 1 is a vertical sectional view through a completely assembled mercury switch embodying the present invention;

Fig. 2 is a top plan view of the mercury switch shown in Fig. 1, the view being taken in the direction indicated by the arrows 2—2; and

Fig. 3 is a diagram indicating the relationship

between the quantity of mercury that flows from one chamber into the other and the time.

Only one specific embodiment of the invention has been selected for the purpose of disclosing the present invention, but it is recognized that many variations will occur to the man skilled in the art, and it is intended that these variations may be made without departing from the scope of the invention.

Referring to the drawings, the invention is shown in the form of a mercury switch, generally indicated at 10, that comprises a switch envelope 11, which is divided into two chambers 12 and 13. The lower portion of the switch envelope 11 has a reduced cross section, as indicated at 14, to provide a shoulder 15 beneath which is mounted a conducting ring 16 that makes good electrical contact with the wall of the switch envelope 11. Both the switch envelope 11 and the conducting ring 16 are preferably made of copper.

The chamber 13 that is shown in Fig. 1 as disposed in the lower part of the switch envelope 11 is completely filled with a slug 17 of material that is provided with a multiplicity of interstices or voids. This slug 17 may comprise sintered nickel or iron particles. These particles are small in size, and the spaces between adjacent particles provide the necessary voids for receiving mercury from the upper hollow chamber 12.

The upper end of the switch envelope 11 is provided with insulating members 18 and 19, over which the upper edge of the envelope wall is turned, as at 20. Between the insulating member 18 and the slug 17 is a copper ring 21 that properly spaces the insulating member 18 from the slug 17 and maintains the chamber 12 free for accommodating a body of mercury, indicated at 22. An electrically conducting member 23 projects through the insulating members 18 and 19 and into the body or pool of mercury 22 in the chamber 12. On top of the insulating member 18 and surrounding the contact member 23 is a metal ring 24, on top of which is mounted an electrically conducting ring 25 that forms one end of a conductor 26. The contact member 23 is turned over at its upper end, as at 27, so as to hold the rings 24 and 25 firmly in place. This electrical conductor 26 forms one contact to the mercury switch, and a second electrical conductor (not shown) is connected to the conducting ring 16.

Under normal conditions, the mercury 22 completely fills chamber 12 of the switch envelope, as shown in Fig. 1. The sintered metal slug 17

is so organized and arranged that under normal conditions it is capable of supporting the mercury 22 in the chamber 12. By spinning the mercury switch 10, or accelerating it in a direction so as to cause the mercury 22 to be forced against the slug 17 as a result of centrifugal force, the mercury, given sufficient time, will flow from chamber 12 into the voids between the metal particles of the sintered slug 17, thereby gradually emptying the chamber 12 to an extent sufficient to lower the mercury level below the contact member 23. Thus, the electrical circuit through the mercury switch, which initially passes from the contact member 23 through the body of mercury 22 and thence through the copper ring 21 and the wall 11 of the mercury switch 10 to the conducting ring 16, is broken.

At the beginning of the operation, which forces the mercury from chamber 12 into the voids in the slug 17, the rate of flow of the mercury is relatively fast, because there is relatively free flow of air or gas throughout the voids, resulting in a rather rapid displacement of this gas. As the interstices between the metal particles are filled by the mercury, however, the flow of gas that is to be displaced is materially restricted, so that the rate of flow of mercury into the slug 17 is retarded. This relationship between the percentage of flow of the mercury from chamber 12 into the voids of the slug 17 and time is diagrammatically shown in Fig. 3 by the curve A. The start of mercury flow is indicated on this diagram at the top of the curve shown at point 28, and it will be noted that during a relatively short time thereafter a rather large percent of the mercury flows into the lower chamber. The curve commences to flatten out at a point indicated at 29 so that the rate of flow decreases as the voids in the slug 17 become filled with mercury.

It is thus seen that a time delay switch has been provided without the use of a wall or partition between the two chambers in the switch envelope and without the use of an orifice that is the only means of restricting the flow of the mercury.

When the slug 17 is produced, it must provide ample voids within its body to accommodate or absorb the mercury that is initially contained in the upper chamber 12. This, the volume of the slug 17 is much greater than the volume of the space that is provided in chamber 12. The time delay in breaking the electrical circuit, of course, is dependent entirely upon the rate of flow of the mercury 22 from chamber 12 into the voids in the slug 17. As soon as the mercury level in the chamber 12 is lowered to a position below the contact member 23, the circuit through the switch is broken.

During the assembly operation, the slug 17 is first inserted through the upper open end of the switch envelope 11. The sleeve or ring 12 of copper is set on top of the slug 17 so as to space properly this slug from the lower end of the contact member 23. The end closure for the envelope 11 is then completed with the electrical contact member 23 sealed in place.

This contact member 23, as shown, is relatively short, though its length in its relationship with the chamber 12 and the slug 17 will depend entirely on the intended use of the mercury switch and the time delay that is required. For a switch having relatively short time delay characteristics, the contact member 23 will be relatively short for given conditions of centrifugal operation. For high spin switches—that is, mercury switches that are operated in such a manner that the body

of mercury 22 produces a relatively great force against the slug 17—the contact 23 will be relatively longer in order to provide a time delay in the breaking of the circuit through the switch.

5 The displacement of gas in the voids or pores of the slugs 17 is caused by pressure of the mercury over the entire surface of the slug 17.

It is apparent from an examination of Fig. 3 that it is possible to select certain portions of the 10 curve A for the limits of the switch operation. In other words, a switch can be adapted to function only over a fraction of the curve A by initially filling a certain percentage of the voids in the 15 slug 17. If this is done, the operation of the switch will commence at a lower position on curve A than the initial point indicated at 28.

Though sintered metal has been mentioned as the material from which the slug 17 may be made, it is recognized that this material may comprise 20 a porous ceramic, or other materials which will provide the necessary porosity and yet will normally support the mercury in chamber 12 until the necessary centrifugal force is produced.

I claim:

25 1. A mercury switch comprising a switch envelope, a porous plug in the envelope adjacent to one end thereof, the opposite end of the envelope being substantially hollow, a body of mercury in the hollow portion of the envelope, and an electrode adapted to contact the mercury in the hollow portion of the envelope, the plug being adapted to absorb sufficient mercury to move the mercury out of contact with the electrode.

30 2. A mercury switch comprising a switch envelope, a porous plug substantially filling at least a portion of the envelope, a body of mercury in the envelope adjacent to the plug, and an electrode adapted to contact the mercury in the hollow portion of the envelope, the porous plug being adapted to absorb sufficient mercury to move the mercury out of contact with the electrode.

35 3. A mercury switch comprising a switch envelope, a porous plug substantially filling approximately half the envelope, a body of mercury in the other half of the envelope, and an electrode adapted to contact the mercury in said other half of the envelope, the plug being adapted to absorb sufficient mercury to move the mercury out of contact with the electrode.

40 4. A mercury switch comprising a switch envelope, a porous plug in the envelope, and a body of mercury in the envelope adjacent to the plug, the plug being adapted to absorb a substantial amount of the mercury.

45 5. A mercury switch comprising a switch envelope, a porous plug in the envelope adjacent to one end thereof, means spacing the plug from the opposite end of the envelope, and a body of mercury in the space remaining in said envelope, the plug being adapted to absorb at least the major portion of the mercury.

50 6. A mercury switch comprising a switch envelope, a sintered metal plug in the envelope adjacent to one end and spaced from the opposite end of the envelope, the said space being adapted to hold a body of mercury, and the plug being adapted to absorb at least a portion of the mercury.

55 7. A mercury switch comprising a switch envelope, a plug in the envelope and provided with multitudinous interstices, and a body of mercury in the envelope, a portion of which is adapted to enter and be held in the interstices.

70 8. A mercury switch comprising a switch envelope provided with a chamber therein, an elec-

trode projecting into the chamber, a porous plug in the envelope adjacent to the chamber and spaced from the electrode, and a body of mercury in the envelope adjacent to the electrode and adapted to emerse at least a portion of the electrode, the plug being adapted to absorb at least enough of the mercury to move the mercury level in the chamber out of contact with the electrode.

9. A mercury switch comprising a switch en-

velope, an electrode projecting into the envelope, a sintered metal mass in the envelope spaced from the electrode, and a body of mercury in the envelope adjacent to the electrode and adapted to emerse at least a portion of the electrode, the sintered metal mass being adapted to absorb at least some of the mercury.

ERNST WALTER RICKMEYER.
